[57] CLAIM

The ornamental design for a golf club head, as shown and described.

DESCRIPTION

FIG. 1 is a perspective view of a golf club head, showing our new design;

FIG. 2 is front elevation view thereof, showing the striking surface of the golf club head;

FIG. 3 is a cross-sectional view taken along lines III—III of FIG. 2;

FIG. 4 is a cross-sectional view taken along lines IV—IV of FIG. 2;

FIG. 5 is a cross-sectional view taken along lines V—V of FIG. 2;

FIG. 6 is a cross-sectional view taken along lines VI—VI of FIG. 2;

FIG. 7 is a rear elevation view thereof, showing the back surface of the golf club head;

FIG. 8 is a top plan view thereof, showing the upper surface of the golf club head;

FIG. 9 is a bottom plan view thereof, showing the sole plate of the golf club head;

FIG. 10 is a right end elevation view, showing the heel of the golf club head; and,

FIG. 11 is a left end elevation view, showing the toe of the golf club head.
